PETROLEUM PRODUCTS SERVICE STATION

Robert Coplon, Verona, N.J., assignor to Supermarkets
General Corporation, Woodbridge, N.J.

Filed July 7, 1970, Ser. No. 23,850

Term of patent 14 years

Int. Cl. D25—03

U.S. Cl. D13—1

FIG. 1

FIG. 2

FIG. 1 is a perspective view of the station; and
FIG. 2 is a top plan view of the station.

The back elevational view is substantially the same as
FIG. 1 with rectangular panels serving as doors.

I claim:

The ornamental design for the petroleum products
service station, substantially as shown and described.
